UNITED STATES PATENT OFFICE

HANS CLEMENT, OF NEW YORK, N. Y., ASSIGNOR TO GENERAL OPTICAL CO., INC., A CORPORATION OF NEW YORK

KRATOMETER

Application filed June 18, 1926. Serial No. 116,771.

This invention relates to ophthalmological apparatus for the diagnosis and treatment of eye defects resulting more particularly from a condition of insufficiency, imbalance 5 or lack of equilibrium of the extrinsic muscles of the eyes. The correction of defects in refraction per se was brought to a high state of perfection by Donders many years ago (some sixty). It was found, however, that 10 refraction alone did not accomplish all that was to be expected from it. Over a further extended period of years methods of diagnosis were developed by which it was gradually learned that there was an interrelation 15 of function between the intrinsic and extrinsic muscles and that in many cases the extrinsic muscles were mostly at fault. At this time, terminating with the work of Noyes, while diagnosis had progressed no satisfactory 20 treatment had been developed. Frequently tenotomy or the surgeon's knife was resorted to but the results were commonly disappointing. It was beginning to be recognized that dynamic exercise and discipline 25 of the extrinsic muscles of the eyes would bring about the desired condition of orthophoria or balance and equilibrium in the functioning of the muscles but at this time there was no suitable apparatus for administering 30 such treatment and such efforts as were made to accomplish this desired result did not meet with much success.

This period of groping came to an end (some thirty years ago) when Hazen invented 35 and put into successful use an apparatus, now known as a kratometer, for exercising the extrinsic muscles and thus innervating the deficient muscles so as to bring about a condition of balance and equilibrium of all of the 40 muscles. Since then improvements in technique of treatment and in the apparatus have been made. More recently it has been found through experience and experiments that not only is there an intimate interrelation or correlation 45 in the functioning of the intrinsic and extrinsic muscles of the eye but that there is also a similar interrelation and correlation of functioning of the muscles between the two eyes of the pair. It was found that the two 50 eyes are not individual entities but that the

pair must be considered as a single binocular instrument and deficiencies corrected from that viewpoint; that the two eyes and their intrinsic and extrinsic muscles function as one complete whole, the pair of eyes as a 55 single binocular optical apparatus and that efforts must be made towards establishing harmony and unity of action among all the parts of this single binocular apparatus, which when functioning properly produces 60 clear single vision. However the apparatus as heretofore developed makes no provision for this new understanding of what is required although considerable advance has been made in the development of a simple 65 technique in carrying forward Hazen's work. The Hazen kratometer employs the jump or step method of treatment, which has been found to be the most effective.

The present invention may be considered 70 as a further development of or as an improvement upon the Hazen kratometer. An object of this invention is to provide a kratometer which will meet the needs arising from the more recent discoveries in physiological 75 ophthalmology. This includes the diagnosis and innervational treatment of the intrinsic and extrinsic muscles of the two eyes of the pair considered as one complete whole, the pair of eyes being considered as a single 80 binocular instrument or apparatus. So far as I am aware such a kratometer or apparatus has not heretofore been proposed. Another object of the invention is to fill a demand for an instrument, the necessity for 85 which has been long recognized, that will enable the refractionist properly to care for the many anomalous cases of eye strain that that not relieved by the prescription of 90 glasses. Another object is to provide a more effective apparatus for successfully treating the cause of those defects of ocular motility 95 that produce eye strain, uncomfortable vision, poor vision, lack of equilibrium, indigestion, headache, slow focussing, and many other complaints. This includes increase in speed of operation in diagnosis and treatment so as not to fatigue the patient unduly; and further includes the embodying in the appa- 100

ratus of everything needed for a complete test or treatment in such manner that adjustment may be made quickly and easily and so that the changes in prism strength may be made successively and accurately in gradations from one strength to the next in successive gradations of prism diopters one after the other, whereby the effect on the eye of one prism is not lost before the next prism can be brought into operating position. Another object is to produce an apparatus by which a more thorough and comprehensive examination can be made than heretofore was possible. Another object is to produce an apparatus by which more effective treatments may be given than heretofore. Another object is to provide an apparatus by means of which all eye defects coming under the general head of imbalance may be successfully treated. Another object is to provide a kratometer so built as to insure the heretofore unobtainable rigidity so essential in giving innervational prism exercises. A further object is to provide an improved kratometer which is compact, simple, light in weight, and easy to operate, as well as neat and attractive in appearance. Other objects and advantages will hereinafter appear.

The invention includes various features of construction and combinations of parts as will appear from the following description.

The kratometer illustrated in the accompanying drawings as one embodiment of this invention will now be described after which the invention will be pointed out in claims, reference now being had to the drawings in which:

Fig. 1 is a front elevation of a complete kratometer embodying my invention with the horizontal prism slides thereof in place;

Fig. 2 is an enlarged vertical section taken on the line 2—2 of Fig. 1;

Fig. 3 is a similarly enlarged front elevation of an end portion of one of a pair of vertical prism slides forming parts of the complete kratometer and which may take the place of the horizontal prism slides shown in Fig. 1;

Fig. 4 is an edge elevation of the same partly broken out and partly in central vertical section as viewed from the right in Fig. 3;

Fig. 5 is a longitudinal vertical section, with parts in elevation, of the complete kratometer taken on the line 5—5 of Fig. 1;

Fig. 6 is a rear elevation of the complete kratometer with parts broken away;

Fig. 7 is a partial vertical section in offset planes substantially as indicated by the zig-zag line 7—7 of Fig. 8, the most of the parts appearing in Fig. 7 being at a higher level than those shown in Fig. 8;

Fig. 8 is an enlarged horizontal section taken on the line 8—8 of Fig. 7;

Fig. 9 is an enlarged rear elevation of what appears in the upper part of Fig. 6, with some

parts removed and with other parts broken away;

Fig. 10 is a horizontal transverse section on the line 10—10 of Fig. 9;

Fig. 11 is a detached front elevation of one of the rotatable battery discs, carrying auxiliary prisms, etc., and which is seen partly in rear elevation in Figs. 6 and 9 at the left;

Fig. 12 is an enlarged front elevation with the middle part broken out of the horizontal prism slide which appears at the right in Fig. 1;

Fig. 13 is an edge view of the same as viewed from the right in Fig. 12;

Fig. 14 is an enlarged front elevation of the detached holding bracket for this slide and which is shown partly in broken lines at the right in Fig. 1;

Fig. 15 is an edge view of the same as viewed from the right in Fig. 14.

Fig. 16 is a rear view of the same and as viewed from the right in Fig. 15.

The mechanical construction as such which constitutes the illustrated embodiment of the invention will be first described with reference to the drawings after which the operation and manner of use will be more particularly set forth. It is to be understood as obvious that many details of construction in the exemplification of the invention shown in the drawings may be departed from without thereby departing from the spirit of the invention. In order to enable a quick grasp and comprehension of the invention and of the construction shown in the drawings for carrying it out, a somewhat general description will now be given to be followed by a description in detail of the several parts and features which are combined to form the complete co-organization which constitutes the kratometer of my invention as a whole.

In the kratometer embodying my invention shown in the drawings two main batteries, designated generally by A and B, are supported upon a triangular base or main frame 1. These batteries are of a similar but reversed construction throughout, the battery A being for the right eye of the patient while the battery B is for the left eye. The battery A is provided with a sight aperture 2 for the right eye and the battery B is provided with a sight aperture 3 for the left eye of the patient. Each battery contains a circular rotatable disc 4, these discs being alike excepting that they are of right and left construction together with all of the parts carried thereby. Each disc is provided with a circular series of nine circumferentially equidistantly spaced auxiliaries comprising an open aperture 5, six supplemental prisms 6, 7, 8, 9, 10 and 11, a Maddox rod 12 and a red glass 13. The prisms 6 to 11 inclusive are respectively of three, five, ten, fifteen, twenty and twenty-five prism diopter strength.

The three, five and ten diopter prisms 6, 7 and 8 and the Maddox rod 12 can be rotated in the disc 4 and may be set at any desired axis. This rotative movement is accomplished by moving the handle 14 of an axis latch which can be moved through a half circle or 180° thereby to rotate these prisms and the Maddox rod through a complete circle or 360° . The lever 15 of the axis latch forms a pointer and the base of any one of these rotatable prisms may be thrown into the desired position by setting the latch lever 15 opposite the words "In", "Out", "Up" or "Down" which appear on a scale formed on the front side of a stationary battery plate 16 which supports the other parts of the battery. The Maddox rod 12 is so mounted in relation to its axis that when the latch lever 15 points at "Up" or "Down" the line of light seen by the eye is vertical, and when the axis latch lever 15 is at "In" or "Out" the line of light appears in the horizontal position.

The fifteen, twenty and twenty-five diopter prisms 9, 10 and 11 are each permanently firmly set on the rotatable disc 4 in such position that the base of the prism will always be outward from the nose of the patient with the prism in register with the sight aperture 2 or 3, since this is the only position in which such strong prisms can be used. The front plate 16 near the top of the battery is provided with a sight opening 17 in plain view from the operator's position and through which he can easily see the indication on the rotatable disc 4 of the particular auxiliary that is in position to be in line with the sight aperture 2 or 3. These indications are placed on the disc 4 one and one-half spaces in advance of the auxiliary which is indicated, as is clearly shown in Fig. 11, when this disc is rotated in the direction to increase the prism strength from prism to prism, it being noted that when rotated in this order the respective discs for the right and left eye turn in opposite directions.

Two pairs of prism-carrying slides, four separate slides in all, form a feature of the apparatus, two of these slides being used at a time. The two slides 18 are duplicates as are also the two slides 19. Each prism slide 18 carries a series of thirteen horizontal prisms 20 firmly secured thereon. The prism power of these prisms 20 ranges successively from one to thirteen diopters in one diopter intervals. An open aperture 21 precedes the one diopter prism and a similar open aperture 22 succeeds the thirteen diopter prisms.

Each of the prism slides 19 carries a series of thirteen vertical prisms 23 which in successive order range in power from 0.25 diopters to 3.25 diopters, in 0.25 diopter steps, these prisms being rigidly fixed upon the slide. Each of the prism slides 19 has an open aperture 24 preceding the prism 23 of

the lowest power and a similar opening 25 succeeding the last or highest power prism.

Each of the prism slides is provided, as shown, with an edge flange and upon the outer side of each of these flanges upon each of the slides indications of the prism powers are marked, as shown in Fig. 13 for the slides 18 having the horizontal prisms 20 and in Fig. 4 for the slides 19 having the vertical prisms 23. The kind of prisms in the slides, whether horizontal or vertical, and also the position of the prism base and apex are indicated by a prism diopter symbol marked upon the front of each end of each of the slides, as shown in the drawings in Figs. 1, 3 and 12.

The above described prism slides are for insertion into slide-holding brackets 26 for longitudinal sliding movement of the slides. These brackets are made of right and left construction. The bracket 26 is mounted upon the front supporting plate 16 so as to be readily removable therefrom and also for rotative adjustment thereon, the sight openings 2 and 3 in the batteries A and B extending also through the respective brackets 26. Each slide 18 or 19 is securely yet slidably held in place at any position of sliding adjustment corresponding to the registering of its respective prisms with the sight opening 2 or 3 by means of a spring pawl 27 to engage in notches shown as formed in the forward edges of the slide flanges, this pawl being carried by the bracket and shown as in the form of a U-shaped leaf spring provided at its ends with inwardly projecting studs to engage in the notches for holding the slide while permitting automatic disengagement of these studs from the notches in the slide, to enable the slide to have unrestricted sliding movement in the bracket. The prism power of the prism of the slide that is before the sight aperture can be noted by the operator in a convenient registering opening 28 (Fig. 15) provided in the lateral outer wall of the bracket 26.

Each bracket 26 can be angled through an arc of 30° to the right or left of the vertical position, thereby to angle the horizontal prism 20 away from the horizontal position or the vertical prism 23 away from the vertical position. The exact horizontal or vertical position of the respective prisms 20 and 23, is indicated when a line forming a marker on the circular base of the bracket 26 is in alignment with a line forming a marker on the stationary front battery plate 16. A set screw 29 in the bracket 26 to be set up against the front plate 16 will hold the bracket and therefore its prism slide rigidly at the desired angle, or in the vertical position. When the slide is to be angled away from the vertical position its set screw is loosened.

Herein when the terms "base in" and "base out" are employed reference is had to the position of the prism base in regard to a ver-

tical plane passing midway between the sight apertures 2 and 3 and therefore midway between the eyes of the patient. With the prism slide 18, having thereon the horizontal prisms 20, used together with the supplemental prisms 6 to 11 inclusive carried by the rotatable disc 4, any base in prism power from one to forty-six prism diopters, and any base out prism power from one to seventy-six prism diopters, can be quickly obtained. By using the prism slides 19 having thereon the vertical prisms 23 in combination with the supplemental prisms 6 to 11 inclusive carried by the rotatable disc 4, any desirable prism power base up or base down in quarter diopter gradients may be quickly obtained.

The pupillary distance between the sight openings 2 and 3 may be adjusted from either side of the apparatus by rotating either one of two knurled knobs 30, such adjustment being indicated by means of a stationary pointer 31 and a movable scale 32 which is easily read from the operator's position. Raising or lowering of the batteries A and B may be accomplished from the operator's end of the instrument by rotating a knurled handle knob 33. Rigidity in position of the vertically adjusted batteries is maintained by means of a locking screw 34 which should be loosened for adjusting the batteries vertically and tightened immediately thereafter. A chin rest 35 may be adjusted vertically by means of a knurled nut 36, and may also be adjusted horizontally forward or back and held by a set screw 37, thereby affording a comfortable rest with the head of the patient in correct position.

A stationary cover plate 38 at the rear of the rotatable disc 4 is secured at its center and its edge to the front plate 16 in spaced relation therewith. This cover plate has secured thereto at its front or inner side a three-armed leaf spring 39 the radial arms of which angle forwardly towards the disc 4 and each of which carries a forwardly projecting stud, one or more of which has a V-end forming a yieldable pawl to engage in one or another of nine equidistantly circumferentially spaced radial grooves 40 formed in the adjacent rear face of the rotatable disc 4, so that the spring 39 forms a latch for yieldingly holding the rotatable disc 4 in adjusted position with any one of its nine auxiliaries in line with the sight opening 2 or 3.

A trial case lens holder 41 is removably secured upon the rear face of the cover plate 38. This lens holder provides three lens cells for the reception of trial case lenses, a usual calibration 42 being provided on the back of the cover plate 38. These rear cells are made of the size specified when the instrument is ordered and are interchangeable with cells of a different size. These rear lens cells are for the purpose of trial case lens cor-

rection for any existing ametropia or presbyopia.

A trial lens holder providing three front lens cells is detachably mounted upon the bracket 26 at the front thereof and comprises two spaced semicircular plates 43 of which the outer plate is calibrated as shown and from the front of which three notched studs 44 project outwardly to the front. The plates 43 are provided as shown with two sets of screw holes either set of which may receive the screws which hold in place the studs 44 and the spacers shown between the plates 43, thereby providing for the reception of either size of trial case lenses now commonly in use. These front lens cells are for the use of cross-cylinder lenses in accommodation-convergence balance tests, and for the addition of weak trial plus or minus spheres or cylinders in this test, also for the reception of plus or minus spheres and loose prisms, the use of which may be desirable while giving exercises. If the patient's prescription includes vertical prisms for constant wear their trial case equivalents may be placed in these front lens cells during exercises of the horizontal functions.

A horizontal forwardly and rearwardly extending rod 45 is provided to hold a test chart carrier 46. The chart holder 46 is free to slide along the entire length of this rod, which is calibrated both in inches and centimeters. This rod is supported upon the base 1 at the front thereof and is mounted so that it may be raised or lowered or if desired it may be entirely removed, a set screw 47 being provided for holding the rod at any desired height. Test cards are provided in sufficient variety for the tests that are to be made and the exercises that are to be given but other test cards may be readily added or substituted in the chart holder 46. The chart holder 46 is so made as to keep all the cards used in near point tests and exercises together, preserving them from loss and soiling and for maintaining them always ready for immediate use.

A stereoscope septum 48, for use in the treatment of suspenopsia and weak fusion, may be slid along and set at any needed place on the rod 45. This septum is rotatable on a vertical axis and when in use it is turned to parallel the batteries, its purpose being to hide the right side of the stereograph from the left eye of the patient, and the left side of the stereograph will be hidden from the patient's right eye. When not in use this septum is turned to parallel the rod 45 and is slid up to the end of the rod next to the batteries where it cannot obstruct the patient's vision.

A breath shield 49 is provided below each of the sight openings 2 and 3 for protecting the prisms in the slides from the moisture

of the exhaled breath, these shields being removable for sterilization.

Details of construction omitted from the foregoing general description will now be described. For each of the batteries A and B the stationary front plate 16 is centrally provided on its inner or rear side with a boss through which passes a reduced forward portion of a shouldered journal stud 50 which is firmly secured in place on the plate 16 by means of a screw 51 threaded into the reduced end of this stud. This stud 50 also has a reduced rear end portion which is screw-threaded to receive thereon a washer-like nut 52. A screw 53, which is threaded into the end of this rear reduced portion of the stud 50, assists in firmly binding together the rear cover plate 38, the stud 50 and the front plate 16.

20 A large spur gear 54 is journaled on the middle enlarged portion of the stud 50, this gear being maintained in place on the stud by the nut 52. At its rear side this gear 54 is shouldered to form a bearing for the rotatable disc 4, which is annular and which is retained in place on the shoulder of this gear by means of a narrow ring 55 which is secured to the gear by means of small screws as shown in Figs. 2, 9 and 10. The rotatable auxiliary prisms 6, 7 and 8 and the rotatable Maddox rod 12 are each firmly secured, respectively, in a rotatable holder 56 journaled in the rotatable carrier disc 4 and each of these holders 56 carries a small spur gear 57 which is of one-half the diameter of the large spur gear 54 with which it meshes. The latch lever 15 is of bent shape and extends inwardly through an arcuate slot 58 in the front plate 16 and at its inner end is firmly secured to the large gear 54, the slot 58 being somewhat more than 180° in length. The latch lever 15 at its outer end carries a small pointer as shown and this latch lever is provided with a slidable latch bolt 59, to which the lever handle 14 is secured. This latch bolt is spring-pressed inwardly for having at its inner end latching engagement with notches in the radially outer edge of an arcuate rib 60 on the front of the plate 16, these notches in the rib 60 being positioned directly radially inward from the hereinbefore mentioned scale indications "Out", "Up", "In", "Down", "Out", respectively.

It will be seen that when the latch lever 15 is rocked by means of its handle 14, the four small gears 57, together with the rotatable holders 56 and the auxiliaries carried thereby, will be rotated at twice the angular rate of movement of the latch lever 15, with the rotatable disc 4 held stationary by its spring latch 39. When the latch lever 15 is held stationary by its bolt 59 and the disc 4 is rotated it will be noted that the rotatable auxiliaries 6, 7, 8 and 12 will also then be rotated by reason of their planetary travel

around the then stationary central gear 54, and this rotation of these auxiliaries will result in bringing any one of them desired for use into the correct position in alignment with the sight opening 2 or 3, the rotative position of such auxiliary being determined by the position of adjustment of the latch lever 15 along the arcuate rib 60.

The slide-holding bracket 26 is provided at each of its four corners with a small guide roller 61 to be engaged by the lateral flanges of the prism-carrying slides 18 and 19, to facilitate the free and easy movement of these slides through the bracket in successively bringing the prisms into alignment with the sight opening 2 or 3. At its back the slide 26 has a circular shoulder by which it is journaled in the front plate 16 and upon the rear face of this shoulder there is secured an annular plate 62 which, at diametral points on its periphery, is provided with projecting radial lugs, as shown, for passing through notches 63 provided in the front plate 16, thereby rendering the entire bracket 26 readily removable and replaceable merely by rotating this bracket in its bearing through an angle of 90°, as will be clear from the drawings.

Each front battery plate 16 is secured, by means of a lug at the bottom thereof, upon the upper end of an upstanding lateral arm 64, the lower end of which is mounted to slide laterally upon a pair of horizontal rods 65 which are rigidly carried by and project oppositely from a head 66. A horizontal screw 67 is provided towards one end with right-hand threads and towards the other end with left-hand threads and is journaled in the head 66 in which it is rotatably held in place by means of a screw stud 68, the inner end of which is shaped to engage in a circumferential groove in the screw 67 at the middle of its length. The right and left hand screw 67 is positioned between the guide rods 65 and has screw-threaded engagement with the battery-carrying arms 64. The knurled knobs 30 are fixed respectively upon the outer ends of the screw 67 and by rotating either the one or the other of these knobs it will be seen that pupillary adjustment of the batteries A and B may be effected. The pointer 31 for indicating the pupillary distance is fixed upon the front face of the head 66 and the movable scale 32 with which this pointer cooperates is fixed at one of its ends upon the front face of the right-hand battery-supporting arm 64. The breath shields 49 are respectively supported by means of a stem 69 which is removably received into a socket 69 shown as provided on the front face of the downward projection on the front battery plate 16 by which it is attached to the arm 64.

The chin rest 35 is slidable forward and back on a short horizontal bar 70 upon which it is held in adjusted position by the set screw 130

37. The bar 70 forms a T-head upon the upper end of a vertical screw 71 which is mounted to have sliding movement through a pair of spaced lugs which project from the rear of the head 66 and between which the adjusting nut 36 is located upon the screw 71 with which it has screw-threaded engagement for adjusting the height of the chin rest 35. The uppermost of these lugs is provided 10 with a screw 71^a the inner end of which engages in a longitudinal slot 71^b in the screw 71, to prevent rotative movement of the chin rest 35 (Figs. 5, 6 and 7). The lower one of these lugs carries a downwardly extending cover tube 72 for the lower portion of the 15 downwardly extending adjusting screw 71.

The head 66 is fixed upon the upper end of a tubular stem 73 which is guided for vertical sliding movement in a collar 74 fixed in 20 the upper end of a tubular standard on the base 1 at the rear thereof, the stem 73 being provided with flats as shown in Fig. 8, to prevent its rotative movement in the collar 74 and standard. The tubular stem 73 has there- 25 in a rotatable adjusting screw 75 which has screw-threaded engagement in the lower portion of the stem 73 and has fixed upon the lower end thereof a bevel pinion 76 which forms a journal for the screw 73 in the base 1 30 and also abuts against the latter to prevent upward movement of this screw, as well as the stem 73 and all of the parts carried thereby, including the batteries A and B. The lower end of this adjusting screw 75 is pro- 35 vided with an adjustable step bearing shown as a vertically adjustable bearing screw 77 threaded into a supporting bracket on the base 1 and provided with a lock nut as shown. The bevel pinion 76 is engaged and driven by 40 another bevel pinion 78 which is fixed upon the inner end of a long horizontal shaft 79 journaled in the base 1 and extending to the outside at the front thereof and upon the forward outer end of which the knurled han- 45 dle knob 33 is fixed, so that by rotating this handle knob thereby the batteries A and B will be vertically adjusted. The locking screw 34 is screw-threaded into the left side of the standard in which the tubular battery- 50 supporting stem 73 slides and at its inner end engages one of the flats on this stem thereby firmly to clamp and hold this stem against any 55 looseness.

The test chart holder 46 is of substantially L-shape and has split rings 80 for removably and replaceably holding the test cards, which may be readily raised or lowered as desired. The holder 46 also includes a mounting block 60 81 provided with a sleeve to slide on the horizontal rod 45, which is of angular cross-section, shown as square, to prevent lateral tipping of the holder 46. The septum 48 has a downwardly extending stem 82 which is pivotally mounted on a vertical axis on a sleeve 65

83 which is slidable along the horizontal rod 45.

The horizontal rod 45 is supported at its ends upon and in spaced relation to a lower parallel rod 84 which at a point intermediate of its length is fixed in a T-head 85, in the construction shown extending farther forward, together with the rod 45, from this head 85 than it extends to the rear, the forward por- 70 tions of these rods 45 and 84 being broken out in the drawings for lack of space. The T-head 85 is rigidly fixed upon the upper end of a downwardly extending stem 86 slidably guided in a cap collar 87 which is firmly fixed upon and extends above the upper end of a vertical tube 88 the lower end of which is rigidly fixed in the base 1. The collar 87 is provided with an internal lug to engage in a longitudinal groove shown in the stem 86, for thereby preventing rotative movement of the stem 86 and the parts carried thereby. The set screw 47, which screws through the collar 87 and tube 88, serves firmly to clamp the stem 86 against looseness as well as to hold this stem in the desired position of vertical adjustment, when it is desired to raise or 80 lower the test chart holder 46.

Perhaps some further explanation as to the operation of the improved kratometer forming the subject of this invention should be 85 added. It should be understood that the prism slides 18 and 19 may be so placed in their holders 26 and so moved therein as to obtain, in combination with the auxiliary prisms carried by the rotatable discs 4, any prism power effect that may be required, base out, base in, base down, or base up. In the drawings (Figs. 1, 5 and 6) for clearness of illustration the two slides are shown at their lowermost position, however, in using this improved kratometer for obtaining similar results for the two eyes of the patient, one of the prism slides would extend downward while the other would extend upward from their respective holders 26 at the beginning 100 of an eye examination or an innervational exercise treatment, so that these slides may be moved in opposite directions either up or down, one by the right hand and the other by the left hand of the operator. The two eyes 105 of the patient may be either tested or treated, both eyes at the same time, and the two slides may be moved simultaneously. The effective prism power at any one time may be either the sum of or the difference between the prism powers of a prism in the slide and a co-operating prism carried by the rotatable disc 4.

The patient is seated comfortably on a stool 110 at the rear end of the kratometer which may rest upon a convenient support such as a table. Proper adjustments are made as to the height 115 of the batteries A and B, of the correct pupillary distance between the sight openings thereof 2 and 3, and proper adjustment is 120 125 130 135

made of the chin rest 35. Also, for near point or convergence work, the chart holder 46 is adjusted to the proper height and to the desired distance along the calibrated rod 45, 5 the stereoscope septum 48, if used, being set to the proper position. For distance work, in which the lines of sight in a pair of normal eyes would be parallel, the chart holder 46 is adjusted downward below the plane of vision. 10 In the drawings (Figs. 1, 6 and 9) the pupillary distance between the sight apertures 2 and 3 is shown at the narrowest, with the inner edges of the battery plates 16 abutting each other, thereby to save space.

15 The operator sits at the front end of the kratometer and somewhat to one side thereof with his right hand positioned below the right-hand battery B, to push the right-hand slide up or pull it down, while his left hand is 20 positioned above the left-hand battery A for pushing the left-hand slide down or pulling it up. The slides may be jumped quickly from a prism of any one power to the next with any desired interval between the jumps, 25 for example, the slides may be thus successively jumped from the prisms of low power to the prisms of high power, or vice versa.

The rotatable prism-carrying discs 4 may be operated in a similar manner for changing 30 the prism powers. With these discs the prism power is increased by moving the top of the disc outward, i. e., away from the nose of the patient. For accomplishing this result most easily the operator should rest his 35 hands on the battery edges with the forefinger extended along the knurled edge of the rotary disc, when a quick drawing in of this finger will rotate the disc to the next higher prism power. In turning the disc in the opposite direction, to reduce the prism power, the finger is bent and a quick shove or straightening of the finger pushes the disc over to the next lower prism.

When prism power base in is desired this 45 may be obtained by rotating the discs 4 to bring in a prism power of five or ten prism diopters, base in, and then neutralizing this with five or ten prism diopters, base out, on the slides, then the slide power may be reduced step by step. With this manner of operation the effective base in prism power before the sight aperture will be the difference between the prism powers of the rotary discs and the prism slides. This saves time by 55 reason of the fact that the prism slides do not have to be withdrawn and reset.

It will be evident that the number of prism power combinations obtainable is large, and the prism powers may be quickly 60 shifted by steps or jumps from one to another.

Among the numerous tests that may be made with this improved kratometer the following may be noted: Phoria tests, for determining esophoria, exophoria, hyperphoria,

or cyclophoria, including distance and convergence tests, and horizontal and vertical tests, the horizontal tests including the abduction and the adduction tests. Also, when required, the Maddox rod may be used in combination with the prisms on the slides. The horizontal phoria tests apply in cases of suspenopsia and suppression, and the vertical duction tests also apply in cases of suspenopsia. Also tests may be made as to 75 stereoscopic vision.

For these and other eye deficiencies the proper dynamic exercises may be given with this improved kratometer for successfully obtaining, in a much shorter space of time than heretofore, the desired normal condition of orthophoria and emmetropia. Exercises may be given for suspenopsia and suppression, for increasing convergence relaxation, for convergence insufficiency, for developing 80 amplitudes and association of accommodation and convergence, for the restoration of binocular functions, in motility and speed of adjustment in various positions, for the treatment of hyperphoria, for developing fusional 85 sense and desire, for the correction of squint, for sectional astigmatism, for oblique astigmatism, torsions and cyclophoria, for amblyopia ex anopsia, etc.

The kratometer, based on principles discovered through experience and experiments, opened an important field which has gradually widened. No single apparatus has appeared that reveals so many of the idiosyncracies of a poorly functioning pair 90 of eyes, nor which is so effective in removing eye deficiencies. It has been found that acuity of vision develops more rapidly under kratometer innervating impulses than by any other method of treatment known. The improved kratometer of the present invention brings this important ophthalmological apparatus into line with the advances 95 made in the science of ophthalmology, thereby to fill the present needs and requirements. For further information on the general subject, reference may be had to the following books: "Ocular Orientation," by Hazen; 100 "Binocular Balance," by Peckham; also other publications.

The kratometer of the present invention is the first instrument to utilize the physiologic principles controlling the functions of ocular versions and binocular single vision. This instrument makes possible the correct diagnosis of many puzzling phenomena leading to ocular imbalance and strain, whose origin and interpretation were impossible by the older instruments and methods. It has been found that the methods of innervational 110 exercising made available with this improved kratometer successfully correct many of these defects, giving comfort to many sufferers for whom previously nothing could be done, 115 120 125 130 135

and that in those milder forms of imbalance which have been successfully treated by the older methods, these improved kratometer methods shorten by more than half the time 5 spent in establishing balance.

It is obvious that various modifications may be made in the construction shown in the drawings and above particularly described, within the principle and scope of the 10 invention as defined in the appended claims.

I claim:

1. An ophthalmological apparatus having, in combination, a pair of stationary members rigidly supported in substantially horizontal relation, a pair of slides one of which is guided on each said member and each slide carrying a longitudinal series of prisms any one of which may be brought into the line of sight of the eye at that side, a pair 15 of independently rotatable discs each mounted upon one of said members and carrying an arcuate series of prisms any one of which may be brought into the line of sight to cooperate with one of the prisms in the slide, 20 a base forming a rigid frame upon which said members are rigidly mounted, a substantially horizontal rod rigidly mounted on the base frame at the front of said members in a vertical plane extending between the lines 25 of sight provided by said members, and a chart holder projecting above and slidable along said rod.

2. An ophthalmological apparatus having, in combination, a pair of stationary members 30 rigidly supported in substantially horizontal relation, a pair of slides one of which is guided on each said member and each slide carrying a longitudinal series of prisms any one of which may be brought into the line 35 of sight of the eye at that side, a pair of independently rotatable discs each mounted upon one of said members and carrying an arcuate series of prisms any one of which may be brought into the line of sight to cooperate with one of the prisms in the slide, 40 a base forming a rigid frame upon which said members are rigidly mounted, a substantially horizontal rod rigidly mounted on the base frame at the front of said members in a vertical plane extending between the lines 45 of sight provided by said members, a chart holder projecting above and slidable along said rod, and a stereoscope septum slidable along said horizontal rod between said members and said chart holder.

3. An ophthalmological apparatus having, in combination, a pair of stationary members rigidly supported in substantially horizontal relation, a pair of slides one of which is guided on each said member and each slide carrying a longitudinal series of prisms any one of which may be brought into the line of sight of the eye at that side, a pair 60 of independently rotatable discs each mounted upon one of said members and carrying an 65

arcuate series of prisms any one of which may be brought into the line of sight to cooperate with one of the prisms in the slide, a base forming a rigid frame upon which said members are rigidly mounted, a substantially horizontal rod rigidly mounted on the base frame at the front of said members in a vertical plane extending between the lines of sight provided by said members, a chart holder projecting above and slidable along 70 said rod, and means providing for the vertical adjustment of said horizontal rod relatively to said members.

4. An ophthalmological apparatus having, in combination, a support, a slide guided on the support carrying a longitudinal series of prisms progressively increasing in prism power through the series and any one of which may be brought into the line of sight, a rotatable disc mounted on the support carrying an arcuate series of prisms progressively increasing in prism power through the series and any one of which may be brought into the line of sight to cooperate with one of the prisms in the slide, means for mounting 80 at least one of said prisms on the disc to provide for its axial rotative movement thereon, and means for axially rotating and setting this prism to any one of four different axial positions on the disc at the line of sight and relatively thereto, viz, base out, base in, base down, base up.

5. An ophthalmological apparatus having, in combination, a support, a slide guided on the support carrying a longitudinal series of prisms progressively increasing in prism power through the series and any one of which may be brought into the line of sight, a rotatable disc mounted on the support carrying an arcuate series of prisms progressively increasing in prism power through the series and any one of which may be brought into the line of sight to cooperate with one of the prisms in the slide, means for mounting a plurality of the prisms of lower power on the disc to provide for their axial rotative movement thereon, and means for concomitantly axially rotating these prisms in unison in the same direction at the same rate and setting them to any one of four different positions on the disc, viz, base out, base in, base down, base up, at the line of sight and relatively thereto.

6. An ophthalmological apparatus having, in combination, a rigidly supported stationary plate provided with a sight opening, a slide guided on the plate provided with a longitudinal series of equidistantly spaced sight apertures any one of which may be brought into line with the sight opening in the plate, a series of successive prisms progressively increasing in power throughout the series rigidly mounted on the slide so as to leave only the end apertures open and to cover all the others, a rotatable disc jour- 120

naled on the plate provided with a complete circumferential series of equidistantly spaced sight apertures any one of which may be brought into line with the sight opening in the plate, and auxiliary optical elements mounted on the disc to cover all its apertures save one left open, said elements comprising a series of successive prisms progressively increasing in power throughout the series followed by a Maddox rod and a red glass.

7. An ophthalmological apparatus having, in combination, a rigidly supported stationary plate provided with a sight opening, a slide guided on the plate provided with a longitudinal series of equidistantly spaced sight apertures any one of which may be brought into line with the sight opening in the plate, a series of successive prisms progressively increasing in power throughout the series rigidly mounted on the slide so as to leave only the end apertures open and to cover all the others, a rotatable disc journaled on the plate provided with a complete circumferential series of equidistantly spaced sight apertures any one of which may be brought into line with the sight opening in the plate, auxiliary optical elements mounted on the disc to cover all its apertures save one left open, said elements comprising a series of successive prisms progressively increasing in power throughout the series followed by a Maddox rod and a red glass, means for mounting a plurality of the successive low power prisms and the Maddox rod to provide for their axial rotation on the disc, and means for concomitantly axially rotating these prisms and the Maddox rod all in unison in the same direction at the same rate and setting them to four different positions when any one of them is in line with the sight opening in the plate, viz., with the prisms base out, base in, base down, base up, relatively to said sight opening, and with the Maddox rod having vertical positions and horizontal positions.

8. An ophthalmological apparatus having, in combination, a support, a rotatable disc mounted on the support carrying an arcuate series of prisms progressively increasing in prism power through the series and any one of which may be brought into the line of sight, a slide guided on the support carrying a longitudinal series of prisms progressively increasing in prism power through the series and any one of which may be brought into the line of sight to cooperate with a prism on the rotatable disc, a trial case lens holder carried by said support adjacent the line of sight outwardly from said disc, and another trial case lens holder carried by said support adjacent the line of sight outwardly from the slide.

9. An ophthalmological apparatus having, in combination, a pair of stationary members rigidly supported in substantially horizontal

relation, a pair of slides one of which is guided on each of said members and each slide carrying a longitudinal series of prisms progressively increasing in prism power through the series and any one of which may be brought into the line of sight of the eye at that side, a pair of independently rotatable discs each mounted upon one of said members and carrying an arcuate series of prisms progressively increasing in prism power through the series and any one of which may be brought into the line of sight to cooperate with one of the prisms in the slide, a pair of trial case lens holders one of which is carried by each of said members outwardly from the slide adjacent the line of sight, and another pair of trial case lens holders one of which is carried by each of said members outwardly from said disc adjacent the line of sight.

10. An ophthalmological apparatus having, in combination, a pair of stationary members rigidly supported in substantially horizontal relation, a pair of slides one of which is guided on each said member and each slide carrying a longitudinal series of prisms any one of which may be brought into the line of sight of the eye at that side, a pair of independently rotatable discs each mounted upon one of said members and carrying an arcuate series of prisms any one of which may be brought into the line of sight to cooperate with one of the prisms in the slide, a base forming a rigid frame upon which said members are rigidly mounted, a substantially horizontal rod rigidly mounted on the base frame at the front of said members in a vertical plane extending between the lines of sight provided by said members, a chart holder projecting above and slideable along said rod, and a stereoscope septum rotatable on a vertical axis and slideable along said horizontal rod between said members and said chart holder.

11. An ophthalmological apparatus having, in combination, a rigidly supported stationary plate provided with a sight opening, a slide rigidly carrying a longitudinal series of prisms, a guide for the slide pivotally mounted on the plate on an axis coincident with the sight opening, releasable means for holding the slide at different angular positions, and a rotatable disc journaled on the plate carrying an arcuate series of prisms any one of which may be brought into line with the sight opening to cooperate with one of the prisms carried by the slide.

12. An ophthalmological apparatus having, in combination, a support, a slide rigidly carrying a longitudinal series of prisms with their bases and apices respectively adjacently directed on parallel lines transverse to the slide, another slide rigidly carrying a longitudinal series of prisms with their bases and apices directed respectively towards the opposite ends of the slide on the same line, means for interchangeably mounting the

slides on said support for sliding movement to bring any prism into the line of sight, a rotatable disc mounted on the support carrying an arcuate series of prisms any one of which may be brought into the line of sight 5 to cooperate with one of the prisms carried by one of the slides, and means providing for setting each of a plurality of the prisms on the disc to different axial positions relatively 10 to the line of sight so as thereby to cooperate with the prisms on the respective slides.

13. An ophthalmological apparatus having, in combination, a pair of stationary members rigidly supported in substantially 15 horizontal relation, a pair of slides guided respectively for sliding movement on said members and each slide carrying a longitudinal series of prisms any one of which may be brought into the line of sight of the eye at that 20 side, a pair of independently rotatable discs mounted respectively upon said members and each carrying an arcuate series of prisms any one of which may be brought into the line of sight to cooperate with one of the prisms on the slide, a base forming a rigid frame provided with a standard, a head rigidly carried by the top of the standard, a pair of lateral arms rigidly upstanding from the head and upon the upper ends of which said 25 members respectively are rigidly carried, and manually operable means engaging said head and arms for moving these arms together with the parts carried thereby simultaneously in opposite directions horizontally for 30 thereby varying the pupillary distance apart of the line of sight provided by said members through said prisms.

14. An ophthalmological apparatus having, in combination, a pair of stationary 40 members rigidly supported in substantially horizontal relation, a pair of slides guided respectively for sliding movement on said members and each slide carrying a longitudinal series of prisms any one of which may be brought into the line of sight of the eye at that side, a pair of independently rotatable discs mounted respectively upon said members and each carrying an arcuate series of prisms any one of which may be brought into the line of sight to cooperate with one of the prisms in the slide, a base forming a rigid frame provided with a standard, a head rigidly carried by the top of the standard, a pair of lateral arms rigidly upstanding from the head and upon the upper ends of which said 45 members respectively are rigidly carried, and a chin rest mounted on the head for both vertical and horizontal forward and back adjustment.

15. The invention defined in claim 13, in combination with means providing for the vertical adjustment relatively to the base of said head together with the parts carried 55 thereby, and a chin rest mounted on the head

for both vertical and horizontal forward and back adjustment thereon.

16. An ophthalmological apparatus having, in combination, a pair of stationary members rigidly supported in substantially 70 horizontal relation, a pair of slides guided respectively for sliding movement on said members and each slide carrying a longitudinal series of prisms any one of which may be brought into the line of sight of the eye at that side, a pair of independently rotatable discs mounted respectively upon said members and each carrying an arcuate series of prisms any one of which may be brought into the line of sight to cooperate with one of the prisms on the slide, a base forming a rigid frame provided with a tubular standard, a tubular internally screw-threaded stem telescoping into the standard, means for rigidly supporting said members upon the upper end of said stem, 80 and a manually rotatable screw journaled at its lower end in the frame and threaded into said stem for vertically adjusting said members together with the parts carried thereby.

17. An ophthalmological apparatus having, in combination, a support, a manually 85 rotatable disc mounted on the support carrying an arcuate series of prisms any one of which may be brought into the line of sight, rotatable holders for mounting a plurality 90 of the prisms on the disc to provide for axially rotating these prisms on the disc, a gear carried by each of these holders, a manually rotatable master gear engaging all of the holder gears, and releasable means for holding the master gear stationary at a plurality of 95 rotational positions thereof, whereby said rotatable prisms will be axially rotated when the disc is rotated and also when the master gear is rotated thereby to bring these prisms to a 100 desired axial position at the line of sight.

18. An ophthalmological apparatus having, in combination, a base forming a rigid frame provided with a front and a rear standard, a pair of stationary members mounted 110 upon the rear standard for unitary vertical adjustment and individual lateral adjustment, a pair of slides guided respectively for independent sliding movement on said members and each slide carrying a longitudinal series of prisms any one of which may be brought into the line of sight of the eye at that side, a pair of independently rotatable discs mounted respectively upon said members and each carrying an arcuate series of prisms any 115 one of which may be brought into the line of sight to cooperate with one of the prisms in the slide, a substantially horizontal rod mounted upon the front standard for vertical adjustment and arranged in a vertical plane 120 extending between the lines of sight provided by said members, and a chart holder projecting above and slidable along said rod.

19. An ophthalmological apparatus having, in combination, a support, a slide guided 125

on the support carrying a longitudinal series of prisms progressively increasing in prism power through the series and any one of which may be brought into the line of sight, 5 a rotatable disc mounted on the support carrying an arcuate series of prisms progressively increasing in prism power through the series and any one of which may be brought into the line of sight to cooperate with one of the 10 prisms in the slide, means for mounting a plurality of the successive prisms on the disc to provide for their axial rotative movement thereon, and means for concomitantly axially rotating these prisms in unison in the same direction at the same rate and setting them to different axial positions on the disc at the line of sight and relatively thereto.

20. An ophthalmological apparatus having, in combination, a pair of stationary members rigidly supported in substantially horizontal relation, a pair of slides guided respectively for sliding movement on said members and each slide carrying a longitudinal series of prisms any one of which may be brought into the line of sight of the eye at that side, a pair of independently rotatable discs mounted respectively upon said members and each carrying an arcuate series of prisms any one of which may be brought into 25 the line of sight to cooperate with one of the prisms in the slide, a rigid main support, a head rigidly carried thereby, a pair of lateral arms rigidly projecting from the head and upon the outer ends of which said members respectively are rigidly carried, and manually operable means engaging said head and arms for moving these arms together with the parts carried thereby simultaneously in opposite directions horizontally for there-by varying the pupillary distance apart of the 30 lines of sight provided by said members through said prisms.

21. An ophthalmological apparatus having, in combination, a pair of stationary members rigidly supported in substantially horizontal relation, a pair of slides guided respectively for sliding movement on said members and each slide carrying a longitudinal series of prisms any one of which may be brought into the line of sight of the eye at that side, a pair of independently rotatable discs mounted respectively upon said members and each carrying an arcuate series of prisms any one of which may be brought 55 into the line of sight to cooperate with one of the prisms in the slide, a base forming a rigid frame provided with a standard, a head rigidly carried by the top of the standard, a pair of horizontal guide rods rigidly carried by the head and each projecting laterally at opposite sides thereof in parallel relation, a pair of lateral upstanding arms the lower ends of which are supported and guided upon said guide rods and upon the 60 upper ends of which said members respective-

ly are rigidly carried, and a horizontal manually rotatable screw journaled in said head and provided towards one end with right-hand threads engaging in one of said arms and provided towards its other end with left-hand threads engaging in the other of said arms for moving these arms together with the parts carried thereby simultaneously in opposite directions horizontally for thereby varying the pupillary distance apart of the 70 lines of sight provided by said members through said prisms.

22. The invention defined in claim 20, in combination with means providing for the vertical adjustment relatively to the said main support of said head together with the parts carried thereby.

23. An ophthalmological apparatus having, in combination, a pair of stationary members rigidly supported in substantially horizontal relation, a pair of slides guided respectively for sliding movement on said members and each slide carrying a longitudinal series of prisms any one of which may be brought into the line of sight of the eye at that side, a pair of independently rotatable discs mounted respectively upon said members and each carrying an arcuate series of prisms any one of which may be brought into the line of sight to cooperate with one of the prisms on the slide, a base forming a rigid frame provided with a tubular standard, a screw-threaded stem telescoping into the standard, means for rigidly supporting said members upon the upper end of said stem, and a manually rotatable screw journaled in the frame and having threaded engagement with said stem for vertically adjusting said members together with the parts carried thereby.

24. An ophthalmological apparatus having, in combination, a base forming a rigid frame provided with a standard, a pair of stationary members mounted upon the standard for unitary vertical adjustment and individual lateral adjustment, a pair of slides guided respectively for independent sliding movement on said members and each slide carrying a longitudinal series of prisms any one of which may be brought into the line of sight of the eye at that side, and a pair of independently rotatable discs mounted respectively upon said members and each carrying an arcuate series of prisms any one of which may be brought into the line of sight to cooperate with one of the prisms in the slide.

25. An ophthalmological apparatus having, in combination, a rigid supporting member, a prism carrier movably mounted on the supporting member carrying a series of prisms of fixed value progressively increasing in steps of prism power through the series and which may be brought successively into the line of sight by the movement

of the carrier to cooperate with a selected prism on a second prism carrier, and a second prism carrier movably mounted on the supporting member carrying a series of 5 prisms of fixed value progressively increasing in steps of prism power through the series and which may be brought successively into the line of sight by the movement of the second carrier to cooperate with a 10 selected prism on the other prism carrier, in combination with means providing for concomitantly reversing the position of the bases and apices of the prisms in one of the said series relatively to the said supporting member, and means providing for 15 concomitantly reversing the position of the bases and apices of the prisms in the other said series relatively to the said supporting member.

20 26. An ophthalmological apparatus having, in combination, a rigidly supported stationary plate provided with a sight opening, a slide rigidly carrying a longitudinal series of prisms, a guide bracket for the slide 25 having on its back a circular shoulder passing through the sight opening and by which the slide is pivotably mounted on the plate on an axis coincident with the sight opening, radial lugs on the inner end of the 30 said shoulder for engagement with the inner side of the plate to hold the guide thereon, the sight opening in the plate being provided with notches for the passage of said lugs to permit the removal and replacement 35 of the guide bracket upon rotative movement thereof, and a set screw carried by the guide bracket to be set up against the said plate for holding the guide bracket and thus the slide at different angular positions.

40 27. An ophthalmological apparatus having, in combination, a rigid main support, a pair of stationary members mounted upon the main support for unitary vertical adjustment and individual lateral adjustment, 45 a pair of slides guided respectively for independent sliding movement on said members and each slide carrying a longitudinal series of prisms any one of which may be brought into the line of sight of the eye 50 at that side, and a pair of independently rotatable discs mounted respectively upon said members and each carrying an arcuate series of prisms any one of which may be brought into the line of sight to cooperate 55 with one of the prisms in the slide.

In witness whereof, I hereunto subscribe my signature.

HANS CLEMENT.
